CONTAINER ASSEMBLING APPARATUS

James E. Annen, Kalamazoo, Mich., assignor to
Sutherland Paper Company, Kalamazoo,
Mich.

Original application September 19, 1938, Serial
No. 230,575. Divided and this application
March 27, 1939, Serial No. 264,405

4 Claims. (Cl. 93—55.1)

This invention relates to improvements in container assembling apparatus.

This is a division of my application Serial No. 230,575, filed September 19, 1938.

5 The main objects of this invention are:

First, to provide improved container assembling apparatus for quickly and easily assembling containers from the elements thereof which are supplied in knock-down shipping form.

10 Second, to provide apparatus of the type described which is simple and inexpensive.

Third, to provide apparatus of the type described which is dependable in operation and can be readily and quickly manipulated by a single 15 operator.

Objects relating to details and economies of the invention will appear from the description to follow. The invention is defined in the claims.

A structure embodying the features of my invention is illustrated in the accompanying drawings, wherein:

Fig. 1 is a side elevation of the apparatus of the invention.

Fig. 2 is a top plan view of the apparatus, 25 being partially broken away to illustrate details of construction.

Fig. 3 is a fragmentary side view in section on line 3—3 of Fig. 2, further illustrating the arrangement of the parts, the parts being shown 30 in operative or container molding position.

Fig. 3A is a view similar to Fig. 3, illustrating the position of the parts in inoperative or discharge position.

Fig. 4 is a view in section on line 4—4 of Fig. 3.

35 Fig. 5 is an enlarged fragmentary view in vertical section, illustrating elements of the container in assembled or erected condition and in operative relation thereof to the apparatus of the invention.

40 Fig. 6 is a detail view illustrating one of the molding segments or elements of the invention.

The present invention relates to an apparatus for assembling container elements to erected condition to form a container suitable for mer-

45 chandising ice cream or similar commodities. A container of the type under consideration is illus-

trated and described in my copending application Serial No. 224,701, filed August 13, 1938. Such a container and the elements thereof are also

50 partially illustrated in Figs. 3 and 5 hereof, consisting of a tubular side wall member 1 which is formed of a suitable grade of container board, in practice folded at opposite diametral points into flat condition for shipping. The said mem-

55 ber 1 has a plurality of segmental sections 2 fold-

ed outwardly against the side wall for locking engagement with the internal lip 3 of an annular channeled metal rim member 4. This rim member 4 likewise surrounds or receives the end member 5 having an annular flange 6 engageable in the channel of the rim member 4. In assembling the elements 1, 4 and 5, the rim member 4 and end member 5 are initially disposed as illustrated in Fig. 5 and the tubular wall member is then inserted within the flange 6 and lip 10 3 by relative movement of the parts in the manner illustrated by the arrow in Fig. 3. It will be understood that some provision is necessary for expanding the collapsed tubular element 1 15 within the rim member 4 and it is with such provision that this invention deals.

The apparatus of this invention consists of a standard or upright 7 mounted on a suitable base 8 and carrying on its top an inclined head 9 20 20 adapted to support the various instrumentalities to be hereinafter described in such position as to be conveniently accessible to an operator.

The head or support member 9 of the embodiment illustrated has a plurality of pairs of 25 pivot ears 10 extending radially therefrom at equally spaced circumferential intervals.

I provide a plurality of complementary segmental conforming elements 11 each having an arcuate or concave downwardly inclined face 12, 30 the faces of the several elements cooperating to provide a continuous annular downwardly tapered or contracting guiding or conforming surface engageable by the tubular side wall member 1 and acting when the side wall member is 35 pushed downwardly therein to erect and conform the same to its erected cylindrical form.

In the embodiment illustrated, each molding element is provided with radially projecting pivot arm 13 terminating in an enlarged boss or 40 knuckle 14 disposed between a coacting pair of ears 10 and receiving a supporting pivot 15 whereby the elements 11 are pivotally or swingably supported on the head. It should be understood, however, that the pivotal mounting of 45 all of the elements is unnecessary as it is unnecessary to retract them all in freeing the work. It is, however, a very practical manufacturing expedient to have all the segments mounted in the same way. The faces of the elements 11 terminate in undercut annular grooves or channels 17 coacting to provide an annular channel adapted to receive the rim of a container with the bottom assembled therein as is shown in Fig. 5. The shoulder 16 above this channel guides the 55

side wall into position so that the rim engaging ledge 2 is brought into position to spring outwardly into the channel rim.

Underneath certain of the pivotally mounted arcuate molding elements 11 I dispose a plurality of tappet members or pins 18. These pins are slideable in apertures 19 in the head 9 and have enlarged heads 20 receivable in counter-bored recesses 21 adjacent the apertures 19. The function of these pins is to elevate certain of the elements 11 when actuated in a manner to be described and thereby free the erected container from the said molding elements for removal therefrom. In the illustrated embodiment there are four such pins 18 for a total of six elements 11, see Fig. 2, it being considered unnecessary and, in fact, undesirable to elevate all of the said elements for removal of the erected container. In fact, it is desirable that one or more of the elements remain resting on the base to enable a rim to be initially positioned in the apparatus for the assembling operation. The rim is of larger diameter than the channel shoulder 16, so that some at least of the forming elements must be withdrawn for its insertion; were all of the elements elevated, it would be difficult to properly position the rim in the forming channel.

In order to elevate the pins 18 as described, I provide a treadle 22 hinged to upright 7 at 23 and to a connecting rod 24 at its free end. The connecting rod 24 is in turn hinged to a pin or plunger release member 25 which is pivoted on the head 9 at 26. The member 25 is provided with a plurality of extensions 27 positioned beneath the pins or plungers 18 to enable the member to engage all of the latter when elevated by the treadle 22 in an obvious manner. The result of such elevation of the plungers is the upward and rearward withdrawal of certain of the elements 11 and the consequent freeing of the assembled container parts 2, 4 and 5 for withdrawal.

The above described device is simple in nature and enables an operator actuating the treadle 22 and feeding container elements to the apparatus to speedily and easily convert the knock-down container elements to finished articles. It is unnecessary to lock up and unlock the segments thereof prior to and subsequent to each assembling operation, as has been the case in certain hitherto known devices. Moreover, this apparatus is ideally suited to the assembly of the particular type of containers referred to above. It is contemplated that devices as described shall be furnished to merchants packaging their products in the containers under consideration for erection of the containers on the premises.

In manipulating the container elements relative to the apparatus, rim 4, with a bottom plate inserted therein, is initially disposed in annular groove 17 with the elements 11 in operative position as illustrated in Fig. 3. The tubular member 1 is then advanced downwardly in either partially or completely collapsed form, as shown in broken lines in Fig. 3, until it engages the molding surface constituted by elements 11. Further movement causes the tubular member to expand to circular form shown in solid lines in Fig. 3, and the assembly is completed when the out-turned container sections 2 pass flange 3 of the rim and snap outwardly into the channel of the same, see Fig. 5, to hold the parts securely in erected position.

I have illustrated and described my improvements in an embodiment which is very practical. I have not attempted to illustrate or describe other embodiments or adaptations as it is believed this disclosure will enable those skilled in the art to embody or adapt my improvements as may be desired.

Having thus described my invention, what I claim as new and desire to secure by Letters Patent is:

1. A container assembling apparatus comprising a supporting upright and base therefor, a forwardly inclined head provided with a plurality of pivot ears, segmental complementary conforming sections pivotally mounted on said ears to normally rest on said head, said sections each having an inner arcuate inwardly tapered conforming surface terminating in an undercut segmental channel, the sections coacting to provide a downwardly tapered annular conforming surface terminating in an annular undercut channel adapted to receive a container rim, said conforming surface being adapted to conform a container wall to cylindrical form as it is pushed downwardly and to guide the same into a rim disposed in said channel, releasing pins for certain of said sections reciprocatingly mounted in said head, a plate pivotally mounted on the under side of said head and having an opening therein receiving said upright, said plate being provided with portions engageable with said pins to actuate the same, and treadle operated means for actuating said plate to engage and actuate said pins, said pins engaging their corresponding sections to pivot the same to release position relative to an assembled container and rim.

2. A container assembling apparatus comprising a head provided with a plurality of pivot ears, segmental complementary conforming sections pivotally mounted on said ears to normally rest on said head, said sections each having an inner arcuate inwardly inclined conforming surface terminating in an undercut segmental channel, the sections coacting to provide a downwardly tapered annular conforming surface terminating in an annular undercut channel adapted to receive a container rim, said conforming surface being adapted to conform a container wall to cylindrical form as it is pushed downwardly and to guide the same into a rim disposed in said channel, releasing pins for certain of said sections reciprocatingly mounted in said head, and a releasing means common to said pins comprising a plate pivotally mounted on said apparatus and having portions engageable with said releasing pins, and treadle actuated means for pivoting said plate to engage and actuate said pins.

3. A container assembling apparatus comprising a head, complementary conforming sections pivotally mounted on said head to normally rest on said head, said sections each having an inner inwardly inclined conforming surface terminating in an undercut channel, the sections coacting to provide a downwardly tapered conforming die terminating in an undercut channel adapted to receive a container rim, said conforming die being adapted to conform a container wall to final form as it is pushed downwardly and to guide the same into a rim disposed in said channel, releasing pins for certain of said sections reciprocatingly mounted in said head, and releasing means common to said pins comprising an element pivotally mounted on said apparatus and engageable with said pins and treadle ac-

tuated means for pivoting said element to engage and actuate the pins.

4. A container assembling device comprising a plurality of arcuate conforming elements, 5 means for mounting said elements whereby to outline a continuous annular mold, said elements each having an inclined arcuate surface and a shoulder adjacent said surface providing an arcuate recess adapted in conjunction with other 10 corresponding surfaces and recesses to provide a continuous annular mold and groove, the latter being adapted to receive a rim for the con-

tainier, said mold guiding and expanding a tubular wall member advanced therethrough to bring the wall member to erected position within said rim, and means for simultaneously swinging a part only of said conforming elements upwardly and outwardly as a unit to disengage the same from the assembled rim and wall member, one or more of the conforming elements remaining in operative mold-outlining position to enable the ready and convenient positioning of a 10 rim thereagainst in the assembling operation.

JAMES E. ANNEN.
